UNITED STATES PATENT OFFICE

WALTER FLIETHER, OF VELBERT, GERMANY

LEAF TURNER

Application filed August 3, 1931, Serial No. 554,844, and in France May 26, 1931.

This invention relates to a music leaf-turner and consists in the provision of a casing from which projects a plurality of pivoted, spring-controlled leaf-turning arms, means being provided for retaining the arms in tensioned position and for releasing them one by one so as to turn the leaves.

Fig. 1 of the accompanying drawing represents a vertical section of a device according to the invention,

Fig. 2 is a horizontal section on the line II—II of Fig. 1,

Fig. 3 is a section on the line III—III of Fig. 2,

Fig. 4 is a side view of the device on a reduced scale, and

Fig. 5 is a view showing the device in operation.

The device comprises a casing 1 containing a central, rigid shaft 4 whereon a plurality of discs 6 are rotatably mounted one above the other. Each disc is recessed for the reception of a spring 7 one end of which is connected to the shaft 4 and the other to the periphery of the disc. Connected to or integral with each disc is an arm 5 which projects radially through a slit in the casing, the arrangement being such that although the discs are situated in different horizontal planes, the arms are maintained in the same horizontal plane. The free end of each arm is upturned and fitted with a leaf-turning plate 8, the latter being preferably encircled by a rubber band 9 in order to reduce the shocks on one plate being thrown by its spring against another.

The plates 8 are inserted between the music-leaves and then turned in opposition to the springs 7 from the position shown in Fig. 2 into engagement with a catch 11 which is adapted to maintain all the arms in tensioned position. The catch 11 is controlled by a spring 13 and bears under the influence of the latter against an inclined surface 14 on a slide 12 which passes through a slot in the catch member. The slide 12 is enclosed in a sleeve 10 and is controlled by a spring 20 in co-operation with which it can be reciprocated through the medium of a wire 19 guided in known manner in a flexible sheath. An-

other catch 17, which is pivotally mounted and controlled by a spring 18, is adapted to enter between the first pair of arms retained by the catch 11. This is effected by means of an actuating rod 16 which is pivoted to the catch 17 and which bears under the influence of the spring 18 against an inclined surface 15 on the slide 12.

The casing 1 is fitted with a sleeve 2 whereby it can be mounted on the supporting pillar of a music stand, as shown in Fig. 5 and secured thereto by means of a set screw 3. The wire 19 may be connected to a foot lever through the medium of which it can be operated for reciprocating the slide 12. By a depression of the foot lever the slide is moved in opposition to the spring 20 and the two catches 11 and 17 will be operated. The latter catch enters between the first pair of unreleased leaf-turning arms and thus retains all the arms with the exception of the first one, and thus the latter is released by the catch 11 which is operated by its spring for turning the respective leaf. When the foot lever is released, the catches return to their initial positions, and the arms still remaining will be retained by the catch 11.

While the device is shown as attached to a self-supporting music stand, it may naturally be attached to a stand mounted on a piano or table, and the foot lever may be replaced by a hand-operated lever.

I claim:

A leaf-turner comprising a casing, a plurality of radial, pivoted, spring-controlled leaf-turning arms projecting from said casing, a spring-controlled slide, a pair of spring-controlled catches bearing against inclined surfaces on said slide and adapted to be operated thereby on the slide being reciprocated, and means for reciprocating the slide, one of said catches adapted normally to retain the arms in tensioned position and to release them on being operated, the other catch adapted, on being operated, to enter between the first pair of unreleased arms and ensure the release of one arm at a time.

WALTER FLIETHER.
